CENTRIFUGAL SEPARATOR

Hans Olof Lindgren, Appelviken, Sweden, assignor to The De Laval Separator Company, New York, N. Y., a corporation of New Jersey

Application January 20, 1933, Serial No. 652,745
In Sweden January 25, 1932

7 Claims. (Cl. 233—46)

In centrifuges having inlets and outlets at the top of the bowl which are tightly connected with fixed pipe lines, the packing boxes effecting a tight joint with the neck of the bowl must be accurately 5 fixed relative to the bowl. Such centrifuges are hereinafter described as of the "closed" type. While it is generally necessary that these packing boxes be removable from the bowl, for the purpose of cleaning both the bowl and packing 10 boxes proper, they must also, during the operation of the machine, be so connected to the frame that they cannot be brought into a faulty position relative to the bowl by outer forces of any kind. The connection between the packing boxes and 15 the frame must therefore be rigid. For practical reasons this connection is effected through the intermediary of a cover or the like positioned over the bowl and forming, with the casing or housing to which it is applied, a chamber enclosing 20 the rotating bowl and separating it from the outer atmosphere; and it is therefore also necessary to make the cover rigid. For centrifuges of not too small a size the cover has large dimensions, and as the thickness of its 25 walls must be considerable owing to the required rigidity, the amount of material in the cover becomes very important. If it is made of iron or a similar material it is so heavy that it is very difficult or quite impossible to lift it off the frame 30 of the centrifugal by hand. By making the cover of a light metal, its weight can be considerably reduced, but this involves an increased cost of material, and for large centrifuges the weight is still too heavy.

35 It is known in the art, in connection with centrifuges of another type than the one described, to make the set of covers corresponding to the cover mentioned above tiltable on a horizontal pin positioned at the side of the frame. The set 40 of covers is then provided with a handle on the side which is opposite to the said pin. A set of covers of this type is of course much more convenient to handle than a set of the usual type which must be lifted off the frame. For a centrifugal separator of the first described type, 45 however, it is not possible simply to make the cover tiltable, because the packing boxes are positioned in its top, and these cannot be removed from the centrifuge otherwise than by being lifted off in the axial direction of the bowl. It is 50 therefore necessary to connect the packing boxes with the cover in such a manner that they can be easily disconnected from it and can be separately removed from the centrifuge. The cover must 55 also be provided with an opening at its top which

is sufficiently large and arranged in such a manner that the supply and discharge pipes which are connected with the bowl are left free when the cover is tilted up.

The accompanying drawing is a vertical sectional view of a closed centrifuge embodying my invention.

Neck 2 of the bowl 1 extends into the packing box system. This system comprises a cover top 16 carrying the packing boxes 3 and fitting in 10 the upper part of the cover 4. The top 16 is held fixedly on the cover by means of a tiltable bale or the like 5, which carries a screw 6 which is screwed against the head 17 of the top 16. At one side the cover is fixed to the separator frame 15 by a hinge 7 fixed to the housing 8 of the frame. The cover is also provided with a handle 9, facilitating the tilting of the cover. The construction of the hinge is such that it does not allow the cover to be tilted to more than a certain angle, for 20 instance, 90° or a little more.

The packing box system comprises at its lower end an annular collecting vessel 10 for leakage liquid, which communicates, by a channel 11, with the space outside the bowl enclosure so that the 25 leakage liquid can discharge. In a centrifuge having tightly connected outlets a certain quantity of liquid may leak past the packings. If this happens at the lowermost packing box the leakage liquid will be thrown out by the bowl against 30 the bowl enclosure. If the liquid thus thrown out is milk, experience has shown that a rather solid annular deposit is formed on the inside of the enclosure at the height of the edge of the 35 bowl which throws out the liquid. The reason why the skim milk which is thrown out in a finely divided state passes into solid form is that the temperature is so high and the amount of leakage liquid is so small that there is enough air contained in the chamber to evaporate the liquid 40 constituents of the skim milk. Since the high temperature is a condition of conversion of the milk from a liquid to a solid state, the vessel 10 is so arranged that its walls become effectively 45 cooled by a stream of air coming from the outside and directed toward the bowl. Between the lower wall of the channel 10 and the chamber 12 is provided an air chamber 13, the lower side of which is bounded by a wall 14 extending near to the bowl. The chamber 13 communicates with the outside air by wide openings 15. A partial 50 vacuum, generated by the rotation of the bowl, prevails in the chamber 13, it being necessary to provide, in the housing of the frame, at a suitable place, an outlet, such as 18, for the air. A 55

strong air stream is thus drawn through the openings 15 and the chamber 18, cooling the walls of the trough 10 so that the milk thrown into the trough is kept in fluid state and can discharge through the channel 11, which is also cooled by the air.

From the above description, the operation will be readily understood. After the screw 6 has been unscrewed, the bale 5 is turned down so that the packing box system can be drawn off the neck of the bowl. The pipe lines (not shown) connected with the packing boxes and referred to in the foregoing description as "fixed" must of course be provided, as is known in the art, with a turnable or sliding joint, or a portion of it must previously be removed from the rest of the system. After the packing boxes have been removed the cover 4 is tilted over so that the centrifugal bowl becomes accessible for cleaning in the usual manner.

What I claim and desire to protect by Letters Patent is:

1. In a centrifuge of the "closed" type, the combination with the bowl and its neck, of a bowl housing, a cover pivotally mounted about a horizontal axis on the housing, a packing box engageable with the bowl neck, a cover top in which the packing box is seated, and means removably securing the cover top in operative position when the cover is swung into closed position.

2. In a centrifuge of the "closed" type, the combination with the bowl and its neck, of a bowl housing, a cover pivotally mounted about a horizontal axis on the housing, a packing box engageable with the bowl neck, a cover top in which the packing box is seated, and means comprising a bale swingable on the cover from a position adapted to permit free vertical movement of the cover top to a position in which it is adapted to fixedly secure the cover top on and in fixed relation to the cover.

3. In a centrifuge of the "closed" type, the combination with the bowl and its neck, of a bowl housing, a cover pivotally mounted about a horizontal axis on the housing, a packing box movable in the direction of the axis of the bowl and thereby engageable with the bowl neck, a cover top in which the packing box is seated, a bale swingable on the cover, and a screw carried by the bale and adapted to be turned to press down the cover top against the cover.

4. In a centrifuge of the "closed" type, the com-

bination with the bowl and its neck, of a packing box engageable with the bowl neck, an enclosure for the bowl, a collecting trough completely surrounding the bowl neck and carried by said enclosure and positioned below the packing box and adapted to receive leaking liquid and provided with a liquid outlet, an air chamber carried by the enclosure, the upper wall of which forms the lower wall of the collecting trough, said air chamber having an air inlet communicating with the 10 atmosphere outside the enclosure and an air outlet communicating with the main chamber formed by the enclosure surrounding the bowl.

5. In a centrifuge of the "closed" type, the combination with the bowl and its neck, of an enclosure for the bowl; said enclosure comprising a lower housing, an open top cover pivotally mounted on the housing, and a packing box mount adapted to close the open top of the cover but removable therefrom; packing carried by the 20 mount and engaging the bowl neck when the mount is in closed operative position, said mount being provided below the packing with a trough adapted to receive leaking liquid and with an air inlet below the trough adapted to supply a current 25 of air to cool the trough wall.

6. In a centrifuge of the "closed" type, the combination with a bowl and its neck, a packing box engageable with the bowl neck and subject to leakage and an enclosure for the bowl, of a leak 30 collecting trough, liable to be heated by conduction from the bowl neck, spaced from it and completely surrounding it below the packing box and provided with a liquid outlet and means providing for a flow of cooling air in contact with the 35 bottom of said trough.

7. In a centrifuge of the "closed" type, the combination with the bowl and its neck, of a bowl housing, a cover pivotally mounted on the housing, a cover top, a packing box seated in the cover 40 top and engageable with the bowl neck, the cover top being movable in the direction of the axis of the bowl to engage the packing box with and disengage it from the bowl neck, and means operable to confine the cover top against the cover, 45 thereby maintaining the packing box in operative position, and to release the cover top to permit it to be lifted in said axial direction and thereby draw the packing box from the bowl neck, the cover being then swingable into position to allow 50 access to the bowl.

HANS OLOF LINDGREN.
